Application March 31, 1951, Serial No. 218,690

3 Claims. (Cl. 220—1)

1

This invention relates to an elevated storage tank.

Elevated storage tanks are employed for the storage of liquids such as water. These tanks have been constructed according to many different designs that consist of a storage portion, a supporting framework for the storage portion, and a foundation, usually of concrete, under the supports. Many of the elevated tanks built in the past have disadvantages in that the foundation is ordinarily quite bulky, and there are problems of getting equal loading on the foundation. If one portion of the foundation settles more than the other portions, strains are set up in the tank and in the supports.

I have invented an elevated storage tank comprising a storage portion, a support means for the storage portion concentrating the load on a relatively small area and permitting the vertical movement of the storage portion under load. There is also provided a bracing means resisting any substantial sideways movement of the storage portion but permitting vertical movement thereof. In this construction the weight of the storage portion and the contents is concentrated on a relatively small area so that the problem of uneven loading of the foundation is substantially eliminated. The actual design of the new elevated tank may vary widely so long as the storage portion is supported on a central member and bracing means are provided to resist sideways movement but to offer very little or no resistance to vertical movement, due to the elasticity of the support. The bracing means may be connected with the storage portion by pivoted members which permit relative movement between the storage portion and bracing means and/or may be totally disconnected with the storage portion to remove all or substantially all of the bending moment in the riser supporting the storage portion, which moment is caused by wind pressure and the like.

The invention will be described as related to one embodiment of the same, as set out in the accompanying drawings. Of the drawings, Fig. 1 is an elevation of a storage tank embodying the invention; Fig. 2 is a vertical section taken along line 2—2 of Fig. 1; Fig. 3 is a horizontal section taken along line 3—3 of Fig. 1; Fig. 4 is similar to Fig. 1 and shows the bracing structure utilized without connection to the storage portion; Fig. 5 is a fragmentary vertical section through a portion of the storage portion and the surrounding ring and bracing structure; Fig. 6 is an elevational view of an alternate construction wherein the bracing structure comprises a ring placed about the riser pipe; Fig. 7 is a fragmentary sectional view taken as indicated by line 7—7 in Fig. 6; and Fig. 8 is a fragmentary vertical section through the lower portion of the storage portion of the tank and the riser pipe showing the bracing structure thereabout.

Referring particularly to Figs. 1 and 4, the

2

elevated storage tank shown comprises a storage portion 10, a combined riser pipe and support 11 for the storage portion, and a framework bracing 12 around the storage portion 10 and riser pipe 11. The riser pipe 11 rests on a concrete foundation 13, while each leg of the bracing 12 rests on foundations 14. The riser pipe 11 and its foundation 13 carry substantially the full weight of the storage portion 10 and the liquid contents of the tank. As can be seen, the entire weight is concentrated on the foundation 13 which covers a relatively small area.

In the embodiment shown in Fig. 6, the storage portion 10 is supported upon a riser pipe 11 resting upon a foundation 13 adapted to support the entire elevated structure with the exception of the bracing. The bracing structure comprises a ring 40 supported by a number of tubular legs 41, herein shown as three in number, equally spaced about the riser pipe. In this embodiment the entire weight of the tank and contents is supported on the foundation 13 and the bracing structure resists sideways movement of the storage tank by bearing against foundations 42 for the tubular legs 41.

When the tank is filled and emptied of liquid there will be a vertical movement set up due to the elasticity of the steel in the riser pipe 11. The bracing 12 which comprises four legs 15, 20 cross cables 16, struts 25, and a circular platform 17 surrounding the storage portion 10, is arranged so that it will not restrict the vertical movement of the tank, but will serve only to prevent any substantial sideways movement due to wind and the like. The bracing is purposely made relatively light in weight, as it is not subjected to any portion of the weight of the tank and its contents.

In order that the bracing 12 will not inhibit the vertical movement of the tank, the bracing is either unconnected to the tank or connected by movable members. If the bracing is unconnected, a clearance of approximately $\frac{1}{8}$ inch between the top of the bracing and the tank 10 may be provided as horizontal deflection of this amount would not result in undue stress. In the embodiment shown the top of each leg 15 of the bracing is connected to the storage portion 10 of the tank by means of substantially horizontal bars 18. Each bar 18 is rotatably attached to the storage portion 10 by means of clevis plates 19 extending from the storage portion 10. A clevis plate 19 is provided on each side of each bar 18 and a pin 20 passes through the clevis plates 19 and the horizontal bar 20. The opposite end of each bar 18 is also rotatably mounted on the legs 15 by means of a second pin 21 passing through two gusset plates 22 and the horizontal bar 18. A gusset plate is arranged on either side of the bar 18. These gusset plates are of substantially triangular shape, and serve not only as an end support for the horizontal bar 18 but also as supports for the horizontal portion 23

of the platform 17. There is a substantial clearance between the inner end of each gusset plate and the storage portion 10 of the elevated tank.

A plurality of substantially horizontal collars 24 are provided around the riser pipe 11. These collars are attached to the legs 15 of the bracing 12 by means of substantially horizontal struts 25. The collars 24 are attached to the riser pipe 11 as by welding while each strut 25 is attached to a collar by means of a flat vertical plate 26 on the collar and a pin 32 connecting the strut and the plate. The outer end of each girder 25 is attached to a leg 15 by means of a second plate 27 attached to a leg 15 with a second pin 33 passing through the girder and the plate 27. Bracing 28 is provided on each strut 25 so as to strengthen the strut, and aid it in resisting bending. Thus each strut is rotatably held at its two ends.

Referring particularly to the structure illustrated in Figs. 4 and 5, the bracing means 12 is entirely unconnected from the storage portion or the riser pipe. The bracing is accomplished by means of a stiff platform 17 having a horizontal portion 23 which may serve as a catwalk about the storage portion. The platform 17 is annular in shape and has an inner member 33 which is spaced approximately $\frac{1}{8}$ inch from the plates of the storage portion when the tank is centered within the bracing means. This platform 17 is rigidly held in position on a plurality of legs 15 suitably braced by cross cables 16 and supported upon individual foundations 14. A gusset plate 22 is provided at the upper end of each leg 15 to provide additional rigidity between the legs 15 and the platform 17. Any wind pressure against the storage tank which causes lateral movement thereof will be resisted when the tank moves sufficiently to come in contact with the inner portion 33 of the platform 17. Bending moment introduced into the tank structure is thus transferred to the bracing structure and carried to the individual foundations 14. While the riser pipe 11 is sufficiently strong to withstand some bending moment, it is desirable to remove a substantial portion thereof so that the riser may be made considerably lighter than would otherwise be necessary.

In the embodiment of the invention illustrated in Figs. 6-8, the bracing ring 40 is placed about the riser pipe a short distance below the bottom of the storage portion 10. Wind pressure acting upon the storage portion creates bending moment in the riser 11 which may be transferred to the bracing structure provided the ring 40 is given sufficient vertical width and is made to fit the riser pipe closely. While the ring 40 fits closely about the riser pipe, sufficient clearance is provided to permit relative vertical movement between the riser and ring. Any number of bracing legs 41 may be provided and it is desirable to provide at least three to gain the requisite stability. The bracing structure may remove all of the bending moment introduced or may remove a portion of the bending moment, leaving the riser to resist the amount not taken up by the bracing structure. In other structures, the bracing means may resist only sideways movement.

As stated above, the ring 40 is likewise closely spaced about the riser pipe. The clearance between the riser and ring permits the tank to settle upon the foundation 13 and to rise and fall with thermo-contraction and expansion of the metal in the riser pipe.

The storage portion 10 may have any shape desired. That shown comprises a generally cylindrical body 29 having a cone top 30 and an inverted cone bottom 31. The riser pipe 11 is connected to the tank at the apex of the inverted cone bottom 31.

The invention is particularly useful in constructing storage tanks having relatively small capacities, such as not more than 50,000 gallons. The size will generally depend upon the thickness of steel used in constructing the riser pipe 11 and upon the resistance of the foundation to compression. In the new storage tank the bracing which resists sideways movement may be used as an erection tower and need only be built strong enough to resist movement of the tank due to wind and the like.

This application is a continuation in part of my application Serial No. 642,336, now Patent No. 2,567,958, filed January 19, 1946.

Having described my invention as related to the embodiment shown in the accompanying drawings, it is my intention that the invention be not limited by any of the details of description unless otherwise specified, but rather be construed broadly within its spirit and scope as set out in the accompanying claims.

I claim:

1. An elevated liquid storage tank structure, comprising a storage portion, a centrally located riser pipe adapted to support the entire storage portion and contents above the ground, a central foundation for the riser pipe, said riser pipe being incapable of supporting the storage portion against substantial sideways movement and means for bracing the tank against substantial sideways movement including, a plurality of columns about the riser pipe laterally spaced therefrom and extending upwardly to a height less than the height of the riser pipe, a ring-like member carried on the upper portions of said columns, said ring-like member and columns being rigid and said columns being capable of preventing substantial sideways movement of the ring-like member, said ring-like member being closely spaced from and encircling the riser pipe adjacent the storage portion concentrically when the riser pipe is centered over said central foundation, said columns and ring-like member preventing movement of the storage portion in excess of permissible movement of the riser pipe from said concentric position to a position in contact with the ring-like member.

2. An elevated liquid storage tank as specified in claim 1 in which said columns carrying said ring-like member are tubular and extend in straight lines between the ground and said ring-like member.

3. An elevated liquid storage tank as specified in claim 1 in which said columns are tubular and are arranged symmetrically about the riser pipe and at least three columns being provided for said bracing means.
